B. BERGER

ELECTRIC HOT WATER HEATER

Filed Jan. 16, 1928

Patented Oct. 16, 1928.

1,688,108

UNITED STATES PATENT OFFICE.

BETTY BERGER, OF NEW YORK, N. Y.

ELECTRIC HOT-WATER HEATER.

Application filed January 16, 1928. Serial No. 246,959.

This invention relates to a new and useful device in the nature of an electric hot water heater using electricity as a medium for heating hot water, and is especially adapted for use in residences and the like, when a supply of hot water is desirable.

The object of the invention is to provide an electric hot water heater of novel construction and arrangement of parts hereinafter more fully described, claimed and illustrated in the accompanying drawing.

Fig. 1 illustrates my improved device as same would appear when in use, certain parts being shown in section.

Fig. 2 is an enlarged vertical sectional view of the heater proper.

Fig. 3 is a schematic wiring diagram thereof.

Fig. 4 is a central sectional view of the water supply valve as embodied in my improved device.

Fig. 5 is a perspective detail view of the valve proper.

Fig. 6 is a perspective detail view of the valve control member.

Fig. 7 is a fragmentary perspective view illustrating a further development of my improved device.

Fig. 8 is a fragmentary sectional view of Fig. 2 showing the modification of Fig. 7 applied thereto.

As here embodied my improved device comprises an electric heater consisting of a housing 10, or shell, of tubular construction, and provided with feet 11, or supports secured thereto at the lower extremity thereof, and extended downwardly therefrom, as a means of supporting the said heater. The housing 10 is provided with a closed lower end 12, and a closed upper end 13. The coil 14, preferably of copper tubing is positioned in the housing 10, the lower portion 15 of the coil 14 extends through an aperture formed in the lower portion of the housing 10. The upper portion 16 of the coil 14 extends through an aperture formed in the upper closed end 13.

My improved device is particularly adapted to be attached to the usual or existing cold water pipe designated by the numeral 17 and which is provided with the usual water faucet 18, positioned over the usual sink 19. The hot water pipe 17 is cut and the usual commercial T 20 is threadedly attached thereto.

The valve body 21 is threadedly attached to the T 20 and is of hollow construction and

has formed therein intermediately a valve seat 22, formed tapered, adapted to receive the valve proper 23, which is provided with a tapered portion 24 and a central extended element 25 and radially extended lugs 26 adapted to slidably engage in the enlarged bore 27 of the valve body 21. The valve control member 28 is of tubular construction and is provided with a threaded portion 29 as a means of attaching the valve control member 28 to the valve body 21. The valve control member 28 is provided with handle elements 30, or lugs, as a means of adjusting, or rotating the valve control member 28, for the purpose as hereinafter set forth. The valve control member 28 is provided with an axial lug element 31 supported by the radial elements 32. The valve control member 28 is provided with a threaded portion 33 adapted to receive the washer 34. The extremity 35 of the lower portion 15 of the coil 14 being formed flanged outwardly, so as to freely engage in the threaded portion 33 of the valve control member 28 and secured therein by the washer 36, suitable rubber washers 37 are positioned adjacent to the flanged portion 35 of the lower portion 15 of the coil 14 and adjacent to the washers 34 and 36 as a means of permitting the valve control member 28 to be freely rotated without the leakage of water. The expansion spring 39 is positioned in the valve body 21 as a means of holding the valve proper 23 in engagement with or in contact with the lug element 31 of the valve control member 28. The above described construction is such as will permit the valve proper 23 to be opened or closed by rotating the valve control member 28 as a means of supplying the desired quantity of water to the above mentioned heater.

The upper portion 16 of the coil 14 is extended, preferably at the rear of the above mentioned sink 19 and has secured at its extremity the usual water faucet 40 positioned over the sink 19.

An electric heater comprising the usual wire 41 suitably coiled so as to provide the required radiating surface is mounted on the usual insulated base 42 positioned at the bottom of the above mentioned heater directly below the coil 14. The heating coil 41 is connected by the wire 43 to the battery 44, or any suitable convenient means of electric current and is connected by means of the wire 45 to the coils 46 of the usual rheostat mounted on the panel 47, which may be secured to the wall

48 and positioned or located adjacent the valve control member 28. The movable contact lever 49 of the above mentioned rheostat is connected by means of the wire 50 to the above mentioned battery 44. The above described construction is such as will permit any desired amount of electric current to be supplied to the heating coil 41 as is required to heat the water in the coil 14. The electric 10 light bulb 51, preferably colored red is mounted in the usual socket 52 and is connected by means of the wires 53 and 54 to the auxiliary rheostat contact lever 49' insulated as at 49^a from the lever 49 and to the battery 56, which 15 is connected by means of the wire 55 to the coils 46 of the said rheostat as a means of lighting the electric light bulb 51 so as to provide a red warning light when the heater is in 20 operation. An electric light bulb 57 of usual white transparent glass is mounted in the socket 58 and is connected by means of the wires 59 and 60 to the rheostat contact lever 49' and to the battery 61, which is connected to the contact point 63 adapted to be engaged 25 by the rheostat lever 49' by means of the wire 62. The latter described construction is such as will provide a white light when the heater is not in operation. It should be understood that the sockets 52 and 58 are mounted 30 on the panel 47.

In Fig. 7 of the accompanying drawing I have shown the valve control member 28 having formed or cut therein, teeth adapted to mesh with the segment gear 65 integral with 35 or secured to the contact lever 49 of the said rheostat. The above described construction is such as will permit the electric current supplied to the heating coil 41 to be automatically increased or decreased when the valve 40 proper 23 is opened or closed. An extension 65 from the gear 64 has at its end another gear 66 meshing with a rack 67 at the top of rod 68 slidably guided along the side of housing 10 down to the bottom thereof and then 45 formed with a U-bend 69. The free arm of this U-bend extends through an aperture in base 12 and connects to base 42 of the heating unit. The heating unit is slidable on guide 70. Upon turning member 28 to adjust valve

23 and arm 49, the gear 66 will also be turned 50 moving rack 67 and rod 68, which will raise or lower the heating unit so as to be nearer or further from the water coils 14. As the valve 23 is opened, the heating unit will move closer to the water coils. 55

While I have above described the preferred form, construction and arrangement of the several elements employed, it will be understood that the device is nevertheless, susceptible of considerable modification therein and I therefore reserve the privilege of resorting to all such changes as may be fairly embodied within the spirit and scope of the invention as claimed. 60

Having thus described my invention, what I claim as new and desire to protect by Letters Patent of the United States is as follows: 65

1. An electric hot water heater, comprising a housing with a water coil, guides connected with the interior of the housing, a heating unit slidably mounted on the guides, and a rod attached to the heating unit and extended from the housing and arranged upon motion for raising or lowering the heating unit so as to be nearer or further from the 70 water coil. 75

2. An electric hot water heater, comprising a housing with a water coil, guides connected with the interior of the housing, a heating unit slidably mounted on the guides, a rod attached to the heating unit and extended from the housing and arranged upon motion for raising or lowering the heating unit so as to be nearer or further from the water coil, and a means for moving and 80 holding the rod in various positions. 85

3. In an electric hot water heater, guides mounted on the heater, a heating unit movably mounted on the guides, and a rod attached to the heating unit and extended 90 from the heater, and arranged for raising and lowering the heating unit, upon motion so as to be nearer or farther from a water coil of the said heater.

In testimony whereof I have affixed my 95 signature.

BETTY BERGER.
